UNITED STATES PATENT OFFICE.

JOHN DITTMAR, OF NEW YORK, N. Y.

DESIGN FOR A CIGAR-CASE.

SPECIFICATION forming part of Design No. 29,221, dated August 16, 1898.

Application filed July 20, 1898. Serial No. 686,469. Term of patent 31 years.

To all whom it may concern:

Be it known that I, JOHN DITTMAR, a citizen of the German Empire, residing in the city of New York, borough of Brooklyn, and 5 State of New York, have invented and produced a new and original Design for Cigar-Cases, of which the following is a specification, reference being had to the accompanying drawings, forming part thereof.

10 Figure 1 is a plan view of one side of the case, showing my new design; and Fig. 2 is a plan view of the other side of the case.

As shown in the drawings, the leading or material feature of my design consists of a 15 triangular part A, projecting upwardly from one end of the oblong body B. The oblong body B is formed with straight and parallel edges b b and with a straight bottom edge b'

at right angles to the edges b b. The edges a of the triangular part extend in V form to 20 and meet the parallel edges b b. The triangular portion A is ornamented with parallel stripes C on one side and on the other side with a striped border C'.

Having thus described my invention, what 25 I claim as new, and desire to secure by Letters Patent, is—

The design for a cigar-case, as shown and described.

In testimony that I claim the foregoing as 30 my invention I have signed my name in presence of two subscribing witnesses.

JOHN DITTMAR.

Witnesses:

GEO. L. WHEELOCK,

GEO. W. JAEKEL.
